UNITED STATES PATENT OFFICE.

LAURITZ C. GARMAN, OF BALTIMORE, MARYLAND, ASSIGNOR TO THE CROWN CORK & SEAL COMPANY OF BALTIMORE CITY, OF BALTIMORE, MARYLAND, A CORPORATION OF MARYLAND.

BOTTLE-CAPPING MACHINE.

1,114,745.

Specification of Letters Patent. Patented Oct. 27, 1914.

Application filed December 20, 1910. Serial No. 598,416.

To all whom it may concern:

Be it known that I, LAURITZ C. GARMAN, a citizen of the United States, residing at Baltimore city, State of Maryland, have invented certain new and useful Improvements in Bottle-Capping Machines, fully described and represented in the following specification and the accompanying drawings, forming a part of the same.

10 This invention relates to certain improvements in bottle capping machines.

The invention has for one of its objects to produce an automatic cap supplying mechanism for bottle capping machines which 15 will be simple and economical in construction and which will operate to deliver the caps with certainty, the construction being such that liability of jamming or breaking caps is decreased.

20 A further object of the invention is to provide a bottle capping machine having a capping head with a cap supplying mechanism including a stationary hopper and improved devices by which the caps are conveyed from the hopper to the capping head.

25 With these and other objects not specifically referred to in view, the invention consists in certain constructions and in certain parts, improvements and combinations 30 as will be hereinafter fully described and then specifically pointed out.

35 Referring to the accompanying drawings—Figure 1 illustrates, in side elevation, a capping machine constructed in accordance with the invention. Fig. 2 is a view similar to Fig. 1, certain parts being broken away and with the capping head in a different position, the front plate of the selecting cage being also removed. Fig. 3 is a detail rear elevation illustrating more particularly the means for operating the selecting cage. Fig. 4 is a front elevation of the construction shown in Fig. 1 with certain parts removed. Fig. 5 is a detail view on a 40 large scale, illustrating the interior construction of the hopper, and the connection of the cap carrying chute therewith. Fig. 6 is a detail plan view.

45 Referring to the drawings, in the particular construction which has been selected to illustrate the invention, 1 indicates a frame or standard in which the several parts of the machine are supported. The construction includes a bottle support, as 2,

which may be of any approved type, that 55 shown being adjustable in the ordinary way, by means of a screw 3. In the particular construction illustrated, the caps are applied by means of a capping head, the detail construction of which may be widely 60 varied. The head is conventionally illustrated at 4, and it may correspond in construction with the capping head now largely employed in applying the well-known crown cork, the construction of such heads being 65 familiar to those skilled in the art. In constructions embodying the invention in its best form this capping head, whatever be its construction, will be movable toward and away from the bottle support. While the 70 means for reciprocating the head may be varied, as shown, the head is provided with an extension 5 secured to an operating rod 6 working through a column 7 attached to the frame 1. In the particular construction 75 illustrated, the head is reciprocated from a power-shaft 8, provided with a crank 9 connected by means of a link 10 to the operating rod. The operation of this power shaft may, as is common in such machines, be controlled from a clutch, not shown, operated by a treadle 11, constructions of this character being well-known to those skilled in the art. If desired, the capping head may be provided with a guiding extension, as 12, 80 working in a guide 13 forming the part of a collar 14 clamped to the column 7.

85 The cap supplying devices employed will, as usual in such constructions, include a hopper, and in the best constructions, this 90 hopper will be stationary. While the particular construction of the hopper and the manner of mounting it may be varied, as illustrated, the hopper 15 is mounted on a rod 16 the lower end of which is secured in a 95 clamp collar 17 bolted to the column 7. The upper end of the rod 16 fits in a socket 18 formed in the hopper casting, a set screw, as 19, being employed, if desired, to hold the hopper firmly on the rod. This construction permits the hopper to be readily placed in position, and also enables this position to be accurately adjusted with respect to the cap applying head.

100 The delivery of the caps from the hopper 105 may be effected by constructions which may be considerably varied. As shown, the hopper is provided with a bearing 20 in which

fits a shouldered sleeve 21, the sleeve serving to support a shaft 22. This shaft has secured to its forward end a selecting cage, the front side of which consists, as shown, of a reticulated conical plate 23 and the rear side of which consists of a plate 24, these plates being connected, in any suitable manner, as by bolts 25. This cage fits into and rotates entirely within a circular opening 26 in the front side of the hopper. The selecting cage will be in open communication with the hopper, so that the hopper may be filled with caps and the caps pass from the hopper into the cage. In the particular construction illustrated, the connection between the hopper and the cage is effected by providing the plate 24 with a centrally disposed orifice 27. In the best constructions this orifice will be provided with an enlargement on one side, the purpose of which is to prevent the binding or jamming of the caps as they pass from the hopper into the cage. While the configuration of the orifice may be varied, as shown the orifice is made circular for a considerable portion of its circumference, and is then enlarged on a regular curve, as indicated at 28, the curve terminating at a substantially abrupt shoulder, indicated at 29, formed on the other side of the opening. As the cage rotates and the enlargement comes into its lowest position, it permits the mass of caps to sag forward somewhat and at the same time any caps which may be jammed will ride up the regular curve, so as to prevent choking.

The cage will be provided with selecting openings, as usual in constructions of this character. While these may be formed in various ways, in the construction illustrated, the openings are formed by shouldered pins 30. The hopper is intended to supply the well-known crown corks which have an attaching skirt flared outwardly at the base, so that the diameter of the crown at the base is considerably greater than at the top. The shouldered pins, therefore, form selecting openings which will permit the crowns to pass through only when the interior of the crowns faces the reticulated plate of the cage. The hopper is provided with a cap receiving channel 31 into which the crowns are delivered from the selecting openings if they are in proper position to pass through them. It may happen that the crowns will be cocked or will enter the selecting openings in such a way as to be caught therein, and when this happens the cage will continue to rotate but some of the selecting openings may be closed by the improperly caught crowns. To prevent this, in the best constructions means will be provided for positively removing improperly caught crowns from the selecting openings. While the construction of the means employed may be varied, as shown there is provided a

tappet consisting of a bent spring 32 which may be secured to the outer side of the cap receiving channel.

The means employed for rotating the selecting cage may be varied. As shown, the outer end of the shaft 22 has secured to it a ratchet wheel 33 on the hub of which are pivoted pawl carrying arms 34 provided with an operating pawl 35, the construction being the usual one. The arms 34 have connected to them a jointed operating rod 36 passing through a guide 37 secured to the extension 5 of the capping head. Springs 38 may be provided located above and below the guide 37, these springs surrounding the rod 36 and being held in position by clamp nuts 39, the object of the springs being to cushion the stroke of the operating rod in each direction.

While the construction by which the caps are conveyed from the cap supplying hopper to the capping head may be varied, it will include a chute. When, as in the best constructions embodying the invention, the hopper is a stationary hopper, this chute should be composed of a plurality of members which are so connected as to have a movement with respect to each other, the chute being thus made extensible to compensate for the varying positions of the head without breaking its connection with either the hopper or the head. While the extensibility of the chute may be obtained in various ways, in the particular construction illustrated, the chute comprises jointed members. As shown, the caps pass from the channel 31 to a chute member 40 pivoted at 41 to the casting which forms the hopper. The chute further includes a member 42 pivoted at 43 to the member 40, and a member 44 carried on the capping head and delivering the caps to the interior thereof, the member 42 being pivoted to the member 44 at 45. This jointed construction provides for the vertical reciprocating movement of the cap applying head, and, furthermore, as the capping head moves up and down, the shifting of the members tends to prevent the caps from becoming lodged or caught in the chute. The sides of the members 40, 42 and 44 may be provided with slots 46, if desired, so that if a cap should be caught in the chute, notwithstanding the movement given the members, it may be readily dislodged.

It will be understood that the construction of the hopper and chute provides for ready delivery of a sufficient supply of caps for capping purposes. Further, by making the hopper stationary, as in the construction shown, the hopper with its load of caps does not have to be raised and lowered as the capping head does, thereby relieving the operating mechanism of the strains incident to raising and lowering the hopper.

It will be understood that changes and

variations may be made in the construction by which the invention claimed is carried into effect. The invention claimed, therefore, is not to be confined to the particular construction herein shown and described.

5 What is claimed is:—

1. In a bottle capping machine, the combination with a bottle support and a capping head, of a cap supplying hopper embodying a rotary cage provided with selecting openings, a spring tappet mounted outside the cage and arranged to enter said openings for positively removing from said openings any caps which may have been 10 caught therein, and a chute for conveying the caps from the hopper to the head.

15 2. In a capping machine, a cap supplying hopper embodying a rotary selecting cage having a rear wall, said wall being pro-

vided with a centrally disposed delivery orifice which is enlarged at one side to prevent choking.

3. In a capping machine, a cap supplying hopper embodying a rotary selecting cage having a rear wall, said wall being provided with a centrally disposed delivery orifice, said orifice having a substantially circular contour for a considerable part of its circumference and an irregularly formed enlargement to prevent choking.

25 30 In testimony whereof, I have hereunto set my hand, in the presence of two subscribing witnesses.

LAURITZ C. GARMAN.
